UNITED STATES PATENT OFFICE.

ROBERT R. NORWOOD, OF MINERALWELLS, TEXAS, ASSIGNOR OF ONE-HALF TO ELISHA V. O'NEALL, OF MINERALWELLS, TEXAS.

LEG-BRACE.

No. 801,901.

Specification of Letters Patent.

Patented Oct. 17, 1905.

Application filed June 23, 1905. Serial No. 266,660.

To all whom it may concern:

Be it known that I, ROBERT R. NORWOOD, a citizen of the United States, residing at Mineralwells, in the county of Palo Pinto and State of Texas, have invented a new and useful Leg-Brace, of which the following is a specification.

This invention relates to a brace for the treatment of ankylosis in the knee-joint.

10 The object of the invention is to provide an appliance of the character specified which will be thoroughly effective in supporting the leg, giving forcible extension to the foot each time it is raised from the ground, thereby to cause 15 the joints stiffened by ankylosis to become supple and resume their normal functions.

A further object is to prevent any interruption of the circulation of the blood through the limb, whereby the normal condition of 20 the limb treated may be maintained under all conditions.

25 A further object is to dispense with the employment of girdles or encircling bands in holding the brace in position upon the limb, whereby discomfort in use is obviated and any tendency to interrupt circulation is prevented.

With the above and other objects in view, as will appear as the nature of the invention 30 is better understood, the same consists, generally stated, in a brace of the character described embodying a pair of supporting members and a plurality of semibands or loops arranged on opposite sides thereof.

35 The invention consists, further, in the various novel details of construction of a leg-brace, as will be hereinafter fully described and claimed.

40 In the accompanying drawings, forming a part of this specification, and in which like characters of reference indicate corresponding parts, Figure 1 is a view in perspective exhibiting a human leg with the brace of the present invention applied thereto. Fig. 2 is a view in perspective of the brace viewed from the opposite side of that shown in Fig. 1. Fig. 3 is a detail view of a slightly-modified 45 form of supporting member.

45 The structure comprises two supporting members each consisting of a strip of flexible material 1, preferably of leather, and constituting, in effect, a splint, and a reinforcing member 2, preferably a resilient wire. Each reinforcing member 2 consists of a length of

wire of suitable diameter secured at the lower 55 end of the splint by a rivet 3, which passes through an eye 4, formed by looping the wire upon itself, the rivet being upset in the splint, thus to insure a positive assemblage of the reinforcing member therewith. The latter 60 member is continued up along one edge of the splint to a point near its top, where it is bent upon itself, as at 5, thence continued down adjacent to the opposite edge of the splint to a point near the bottom thereof, 65 where it is bent upon itself, as at 6, and thence continued up to a point near the top of the splint, where it terminates adjacent to the bend 5. The upper end of the reinforcing member is held combined with the splint by 70 having the upper terminal of the latter folded over the bend 5, as shown at 6, and by passing a rivet 7 through the overturned portion of the splint between the bend 5 and clenching it to the body of the splint, as shown at 8. 75 The reinforcing member is further positively combined with the splint by keepers 9, 10, 11, and 12, each of which consists of a length of leather looped around the reinforcing members, as shown in Fig. 1, and positively combined with the splint by a rivet or rivets 13, one rivet being shown used in connection with the keepers 9 and 12 and two rivets used in connection with the keepers 10 and 11.

Connected with the supporting members 85 are five semibands 14, 15, 16, 17, and 18, the bands 15 and 16 being adapted to be disposed above and below the knee-cap, and the bands 14, 17, and 18 being adapted to occupy a position at the rear of the leg slightly above the 90 knee and at points adjacent to the angle. Each of the semibands is constructed of leather, and has its edges beveled, as at 19, thus to prevent discomfort in use, the splints being similarly beveled at 20 for the same 95 purpose. The semibands are held combined with the splints by adjusting-straps 21, 22, 23, 24, and 25, each of which is provided at one terminal with a buckle and at its other terminal with a plurality of orifices to engage the buckle-tongue to hold the strap under the desired tension, and the straps are secured to the semibands by rivets 26. The strap 21 engages the bend 5 of the reinforcing member and is held against downward 100 movement by the keeper 9. The straps 22 and 23 engage the outer members of the reinforce and are disposed between the keepers 105

10 and 11, and are thus held against upward and downward movements, respectively. The strap 24 engages the lower bends 6 of the reinforce and is held against upward movement 5 by the keepers 12, and the strap 25 engages the lower portion of the reinforce. The reason for combining the straps 21, 22, 23, and 24 with the supporting member in the manner described is positively to hold them against 10 movement, so that when the semibands are once adjusted upon a limb there will be no danger of slippage.

It will be seen by arranging the semibands in staggered order—that is to say, alternately 15 on opposite sides of the leg—that all danger of interfering with the circulation is prevented, and, furthermore, no discomfort in use will result, which would be inevitable if the girdles or encircling bands were employed for 20 holding the appliance in position, as these would have to be drawn sufficiently tight to hold them from movement, and would thus inevitably interfere with the circulation, and thus cause pain in use of the appliance.

25 A further feature of novelty is that by having the semibands relatively broad and the attaching-straps 21 to 25, relatively narrow these latter will not contact with the limb, but will only serve to force the broad semibands against 30 the limb, and these latter will not cause any uncomfortable sensation in walking.

In order to prevent accidental separation of the semibands from the supporting members when the appliance is not in use, the 35 buckles are preferably connected to short straps 27, which are combined on one side with the supporting members in the same manner as the last-named straps.

40 As herein shown, the reinforce member is constructed of a single piece of wire bent in the manner described; but it is to be understood that under some conditions where an extra amount of force is required in flexing the limb the reinforce should be stronger, and 45 to meet this emergency each of these members may be made of two or more wires without departing from the spirit of the invention, or, as shown in Fig. 3, the reinforcing member 27 may be made of a single length of wire 50 formed at its center with an eye or loop 28 and having one terminal bent upon itself to form a loop 29, the ends of the member being secured to the splint 30 by rivets 31. This form of supporting member will be found 55 thoroughly efficient in use in some cases where excessive strain is not required upon the limb.

While the device has been described as par-

ticularly adaptable for use in the treatment of ankylosis of the knee, it is to be understood that it is adaptable for use in treating other 60 weaknesses of the knee or leg, and therefore the invention is not to be limited to treatment for any particular ailment.

It will be seen from the foregoing description that although the improvements herein 65 defined are simple in character they will be thoroughly efficient for the purposes designed and will result, without causing pain, in effecting the gradual but positive straightening of the limb and at the same time restoring its 70 natural functions.

Having thus described the invention, what is claimed is—

1. A brace embodying a pair of supporting members, and a plurality of semibands or 75 loops arranged on the opposite sides thereof.

2. A brace embodying a pair of supporting members and a plurality of adjustable semibands or loops arranged on the opposite sides thereof.

3. A brace embodying a pair of reinforced supporting members and a plurality of adjustable semibands arranged on opposite sides of the members and combined with the reinforces.

4. A brace embodying a pair of reinforced 85 supporting members, and a plurality of semibands arranged on opposite sides of the members and combined with the reinforces.

5. A brace embodying a pair of splints, longitudinally-disposed reinforces combined with 90 the splints, keepers secured to the splints and operating to hold the reinforces in position thereon, and semibands or loops held in position by the keepers and by the reinforces.

6. A brace embodying a pair of splints, ex- 95 teriorly-disposed reinforces combined therewith, keepers encircling the reinforces and secured to the splints, a plurality of semibands, and straps secured to the semibands and engaging the reinforces and held in proper position by the keepers.

7. A brace embodying a splint and a reinforcing member combined therewith and comprising a length of wire having its intermediate portion formed into an eye, and one of its 105 terminals formed into a loop.

In testimony that I claim the foregoing as my own I have hereto affixed my signature in the presence of two witnesses.

ROBT. R. NORWOOD.
